AUGUST SUNDH, OF HASTINGS-UPON-HUDSON, NEW YORK.

AUTOMATIC BLOCKING MECHANISM FOR STRIP-MILLS.

1,262,135.

Specification of Letters Patent. Patented Apr. 9, 1918.

Application filed March 24, 1916. Serial No. 86,328.

To all whom it may concern:

Be it known that I, AUGUST SUNDH, a citizen of the United States, residing in Hastings-upon-Hudson, in the county of 5 Westchester and State of New York, have invented a new and useful Improvement in Automatic Blocking Mechanism for Strip-Mills, of which the following is a specification.

10 My invention relates to an improvement in automatic blocking mechanism for strip mills, and I have provided means whereby a strip may be blocked automatically and at the same time without any danger of buckling of the strip, as the strip does not have to actuate any electrical devices, such as switch arms, etc.; the strip does not have to carry an electric current at any time, thus avoiding the danger of burning the strip 15 and ruining it; I do not have to use any grounded circuits, which are so often a source of trouble by reason of the foundations for the machine becoming grounded, and also giving shocks to users of the 20 machine. These and other advantages of the present apparatus will be more fully pointed out hereinafter.

Referring to the drawings wherein my apparatus is illustrated, Figure 1 is a plan view partly in section of the whole apparatus; Fig. 2 is an elevation view also partly in section, and showing the strip entering the block from the mill rolls; Fig. 3 is a longitudinal section through the block, 35 showing its interior structure; and Fig. 4 is an end view of the mill rolls showing the contact device which controls the operating mechanism of the block.

In general my apparatus comprises a contact mechanism normally held out of operative position by the mill rolls when a strip is not passing therebetween, but adapted to be actuated when a strip is passing between the mill rolls. This contact mechanism 45 closes a circuit to a relay which in turn controls a valve which when operated admits fluid to a piston directly connected to the inside of the block, to expand clamping mechanism therein to attach the strip to the 50 block. The relay or timing device is adjustable, and is entirely independent in its operation of the feeding movement of the strip, being actuated to operative position so soon as the strip enters between the mill 55 rolls. This timing device is set so that it

will have functioned to cause the clamping mechanism inside of the block to expand as soon as the strip has entered the block.

The block, that is to say the member on which the strip is wound, comprises an outer 60 cylindrical, sectional casing 1, the sections of this casing being hinged together so as to permit of the casing collapsing, so that the strip, after it has been blocked, may be easily removed therefrom. A hollow shaft 2 is 65 carried within the casing 1 and extends the entire length of the block and rearwardly, as viewed in Fig. 1, through bearings 3, gear 4, and bearings 5. Secured to this shaft 2 at its forward end is a member 6, which 70 carries the collapsible members 7, which form means for gripping the strip to be blocked. These members 7 are pivoted to the member 6 at one end, toggles 8 supporting the other end. These toggles are secured 75 to a rod 9 extending rearwardly through the hollow shaft 2, to a piston 10 in a cylinder 11 carried on the hollow shaft 2 and rotatable therewith. It will be seen from the 80 description thus far given, that movement of the rod 9 to the right, as viewed in Figs. 1 and 3, will cause the toggles 8 to be straightened out and the inside members 7 of the block forced outwardly to grip the strip between them and the inside of the outside casing 1. An opening 12 is provided 85 between two of the sections of the casing 1 for the reception of the end of the strip as it reaches the block. A hand wheel 13 is provided, secured to the casing 1 of the 90 block, to rotate the same so that the opening 12 may be in alignment with the end of the strip as it reaches the block. A small compression spring 14 is provided as shown in Fig. 3 to bear on the outside of the casing 95 1 to hold the same in place after the opening 12 has once been rotated into proper position as heretofore described. The hollow shaft 2 is rotated, constantly if desired, by means of an electric motor M and gears 4 and 15, and as this hollow shaft carries the inner mechanism of the block it will be seen that this mechanism rotates also.

I will now describe the mechanism which controls the expanding of the inner mechanism of the block. In rolling mills of the type used in conjunction with strip blocking mechanism, the upper roll, in this instance designated 16, lifts slightly, and I utilize this feature of the mill rolls to operate my

contact mechanism which controls the expanding mechanism of the block. A support 17 is secured to one end of the rolling mill. Pivoted on this support at 18, is a 5 contact arm 19, carrying a contact 20 at one end, its other end carrying a member 21, normally bearing against the mill rolls, being held against the rolls by a compression spring 22. When the mill roll which will 10 be raised due to the strip of metal passing under it, is lifted, the member 21 will be forced in between the rolls by the action of the spring 22, and the contact 20 will be moved into engagement with a stationary 15 contact 23 carried on the support 17. I have shown in Fig. 4 the end of the member 21 which enters between the mill rolls beveled slightly, so that after the strip has passed through the rolling mill, the upper roll in 20 settling back to its normal position, will force the member 21 out from between the rolls to open the contacts 20 and 23. The contacts 20 and 23 control a circuit of a winding 24 of an electromagnet E, this winding 25 receiving its power from any suitable source of supply. I have shown the armature of the electromagnet E working within a dashpot D, the action of this dashpot being adjustable by means of a slotted screw 30 26 which enters the lower end of the dashpot chamber 27. This armature, designated 25, actuates an arm 28, pivoted at one end at 29, and carrying on its other end a contact 30. Pins 31 in the armature, one on 35 each side of the arm 28 will cause the armature when raised to actuate the arm 28, to bring the contact 30 into engagement with a stationary contact 31. As the armature 25 has to work against the action of the 40 dashpot, and as the action of this dashpot may be varied by means of the screw 26, it will be seen that the time within which the contact 30 will engage the contact 31, after winding 24 is energized may be varied 45 to suit varying conditions. Closing of the contacts 30, 31, closes a circuit for a winding 32 of an electromagnet 33, in the present instance deriving its power from the same source of supply as the electromagnet 24. 50 Energization of the winding 32 raises the core 34 of the magnet 33, the lower end of this core forming valve mechanism. 35 designates a supply pipe for conveying fluid under pressure from any suitable source of 55 supply, this fluid being permitted, when the armature 34 is in raised position to flow down by or through the armature, through a pipe 36 to the inside of the chamber 11, which as before pointed out is rotatable with 60 the hollow shaft 2, to force the piston 10 to the right as viewed in Fig. 1. A spring 37 is provided on the opposite side of the piston 10 from which the fluid enters the chamber 11, to force the piston back to the 65 left, and to force the fluid within the cham-

ber out up through the pipe 36 and by a discharge pipe 38 to the outside again, when the electromagnet 33 has been deenergized and its core dropped.

A cycle of operation of the apparatus described is as follows: As the strip S enters between the upper roll 16 and the lower roll of the rolling mill, the roll 16 is slightly raised, and the arm 19, actuated by the spring 22 will close the contacts 20 and 23, 70 the member 21 at the same time entering between the mill rolls. Closing of these contacts will close a circuit to the winding 24 of the electromagnet E, which will then draw up its armature 25. By reason of the 75 pin connection of this armature 25 with the contact arm 28, the latter will be raised to close the contacts 30 and 31, to close a circuit to the winding 32 of the electromagnet 33. This magnet in turn will raise its armature 34 to open the valve admitting fluid to the pipe 36 and from thence to the chamber 11, on the left side of the piston 10. The piston 10 will be forced to the right, the fluid being under pressure of course, and with it carry the rod 9. As the rod 9 is carried to the right it expands the inside members 7 of the block, by reason of the toggles 8 being straightened out, and the strip S, which by this time has reached the 85 block and its end entered to the inside of the block through the opening 12, will be gripped between the inside members of the block and the inside of the outside casing 1 of the block, and as the inner mechanism 90 of the block is rotating at this time, it will be seen that at this instant the whole block will start to rotate, and the strip be wound around the periphery of the block. When the strip has traveled far enough that its 105 end rides out from between the mill rolls, the upper roll will settle back into place, force the member 21 out from between the rolls, which will actuate the arm 19 to open the contacts 20 and 23. Opening of these 110 contacts breaks the circuit to the winding 24 of the electromagnet E, its armature will drop back, and carry with it the arm carrying the contact 30, which will open the circuit for the electromagnet 33. This magnet 115 in turn will drop its core, its winding now being dead, which will shut off the fluid from the supply pipe 35 and open the port of the discharge pipe 38. The spring 37 within the casing 11 will now force the piston 10 to the left, the fluid back of the piston being free to be forced out through the discharge pipe 38. This movement of the piston 10 to the left will cause the rod 9 to be carried to the left also, to collapse 120 the inside of the block, and the outside casing 1 of the block, by reason of its sections being hinged together will also be free to collapse, and the roll of metal may easily be 125 removed.

I prefer to employ some incompressible fluid such as water or oil, for operating the strip-attaching mechanism of the block, for the reason that a great tension is exerted on the block when the strip is being blocked, and the block would possibly be collapsed slightly if the fluid holding it expanded were not incompressible, and if it did collapse the strip would be buckled and destroyed. With this arrangement and using an incompressible fluid, strips of varying thickness may be blocked without adjusting the machine each time.

The advantage of having the throw of the armature of the electromagnet E adjustable, is now obvious, as should one strip be fed faster than the preceding strips, it is merely necessary to shorten the throw of this armature, by adjusting the screw 26, to cause the electromagnet's armature to have to be moved a shorter distance than before, before closing the contacts 30 and 31. The effect of this, of course is to permit the inner mechanism of the block to be expanded sooner than before, which will be necessary as the strip in this instance is being fed faster than the preceding strips, and consequently will reach the block sooner than the other strips did. Another advantage of this adjustment is that the throw of the electromagnet may be adjusted to an exact nicety so that the strip may be allowed to enter the inside of the block only to a desired amount before being clamped.

Another feature of advantage in my arrangement is that the means for expanding the inner mechanism of the block and the block itself are in alinement, so that no complicated lever systems have to be used or 40 thrust bearings, and as the power acts on one end of a shaft and the expanding mechanism is on the other end, a rigid connection is thus provided between the two, so that the two though separated are directly connected 45 to each other.

I wish not to be limited to the precise construction and details of parts herein disclosed, as others skilled in this art might make various changes therein without deviating from the spirit and scope of the invention.

What I claim and desire to secure by Letters Patent of the United States is:—

1. In blocking mechanism adapted to wind a strip fed from a strip mill, the combination of a rotatable block, means for clamping the strip to the block, fluid pressure means for operating said clamping means and means operating by bodily movement of the mill rolls for automatically controlling said fluid pressure means.

2. In a blocking mechanism adapted to wind a strip fed from a strip mill, the combination of a rotatable block, means for clamping the strip to the block, fluid pressure

means for operating said clamping means, and electrical means controlled by the strip for controlling said fluid pressure means.

3. In a blocking mechanism adapted to wind a strip fed from a strip mill, the combination of a rotatable block, means for clamping the strip to the block, fluid pressure means for operating said clamping means, and automatic electrically controlled means controlled by the strip for controlling said fluid pressure means.

4. In a blocking mechanism adapted to wind a strip fed from a strip mill, the combination of a rotatable block, mechanism for clamping the strip to the block, and a rotatable fluid pressure device rotatable with the block for operating said block clamping mechanism.

5. In a blocking mechanism adapted to wind a strip fed from a strip mill, the combination of a rotatable hollow shaft, a block on one end of said shaft, mechanism in said block for clamping the strip to the block, a rotatable fluid pressure device on the other end of the hollow shaft, and means connecting said fluid pressure device with the clamping mechanism of the block through said hollow shaft.

6. In a blocking mechanism adapted to wind a strip fed from a strip mill, the combination of a rotatable block, expandible strip-attaching mechanism within said block, a fluid pressure device for expanding said strip-attaching mechanism, and electric automatically controlled means controlled by the strip for controlling said fluid pressure device.

7. In a blocking mechanism adapted to wind a strip fed from a strip mill, the combination of a rotatable block, expandible mechanism within the block for attaching the strip to the block, a fluid pressure cylinder rotatable with the block and adapted to control said expandible mechanism, and means for carrying fluid pressure to and from said cylinder when rotating.

8. In a blocking mechanism adapted to wind a strip fed from a strip mill, the combination of a rotatable block, means for clamping the strip to the block, fluid pressure means for operating said clamping means, said fluid pressure means comprising a cylinder and a piston and a valve for admitting fluid pressure to and from said cylinder, and an electroresponsive device controlled by the strip for controlling said valve.

9. In a blocking mechanism adapted to wind a strip fed from a strip mill, the combination of a rotatable block and a rotatable fluid pressure cylinder, a piston in said cylinder, means to connect said block and said piston, and means to admit fluid to the cylinder to control the block while the block is rotating.

10. In a blocking mechanism adapted to wind a strip fed from a strip mill, the combination of a rotatable block, fluid pressure means for operating said block, and a device operating as the strip enters the strip mill rolls for automatically operating said fluid pressure means.
11. In a blocking mechanism adapted to wind a strip fed from a strip mill, the combination of a rotatable block, fluid pressure means for operating said block, and a device controlled by bodily movement of a roll of the strip mill independent of rotation of said roll for controlling the operation of said fluid pressure means.
12. In a blocking mechanism adapted to wind a strip fed from a strip mill, the combination of a rotatable block, a fluid pressure device for operating said block, an electro-magnetically operated valve for controlling the fluid pressure, and means to automatically control said electro-magnetically controlled valve in proportion to the feeding movement of the strip, and thereby cause the strip to be attached to the block when it reaches the block.
13. In a blocking mechanism adapted to wind a strip fed from a strip mill, the combination of a rotatable block, fluid pressure means for operating said block, and an electroresponsive device controlled by an automatically controlled circuit for controlling said fluid pressure.
14. In a blocking mechanism adapted to wind a strip fed from a strip mill, the combination of a rotatable block, mechanism in the block for clamping the strip to the block, a fluid pressure cylinder, a piston in said cylinder, mechanism connecting said piston and the clamping mechanism, a valve for admitting fluid to and from said cylinder, an electroresponsive device for controlling said valve, a circuit for said electroresponsive device, said circuit being controlled in proportion to the feeding movement of the strip, whereby the strip will be clamped to the block through the intermediate electroresponsive device and fluid pressure means when the strip reaches the block.
15. In a blocking mechanism adapted to wind a strip fed from a strip mill, the combination of a rotatable block, fluid pressure means for operating said block, an electrically controlled valve, an adjustable timing device working in proportion to the feeding movement of the strip to control the fluid and cause the fluid pressure means to operate the block and clamp the strip at a predetermined moment.
16. In a blocking mechanism adapted to wind a strip fed from a strip mill, the combination of a rotatable block, an electric circuit controlled by the mill rolls and when the strip goes through the mill, a timing device in said circuit and controlled thereby,

the timing device being adjustable, and means controlled by said timing device adapted to operate the block to clamp the strip to the block at a predetermined moment.

70

17. In a blocking mechanism adapted to wind a strip fed from a strip mill, the combination of a rotatable block, clamping means embodied in the block, an electric circuit closed by the action of the mill rolls when the strip is sent through the mill, an adjustable timing element controlled by said circuit operating in proportion to the feeding movement of the strip, to cause the clamping means to clamp the strip to the block at a predetermined instant.

75

18. In a blocking mechanism adapted to wind a strip fed from a strip mill, the combination of a rotatable block, clamping means embodied within the block, means to operate said clamping means, means for controlling the said clamp operating means, a circuit therefor controlled by the mill rolls when the strip is sent through the mill, to cause the strip to be clamped at a predetermined moment.

85

19. In blocking mechanism adapted to wind a strip fed from a strip mill, the combination of a rotatable block, a clamping mechanism embodied in said block, a cylinder, a piston in said cylinder, connections between said piston and the block clamping mechanism, said piston adapted to be controlled by non-compressible fluid pressure, and automatic means controlled by the strip for controlling this pressure.

95

20. In a blocking mechanism adapted to wind a strip fed from a strip mill, the combination of a rotatable block, a clamping mechanism embodied within the block, said clamping mechanism being sectional, toggles connecting the sections of said clamping mechanism, a cylinder, a piston in said cylinder, means for connecting the toggles and said cylinder, and fluid pressure means for actuating said piston to actuate the toggles to operate the clamping mechanism.

110

21. In a blocking mechanism adapted to wind a strip fed from a strip mill, the combination of a rotatable block, a clamping mechanism embodied within said block and operated with toggles, a cylinder, a piston in said cylinder, means connecting the piston and the said toggles, and non-compressible fluid pressure adapted for actuating said piston to hold the toggles in position to clamp the strip to the block.

115

22. In a blocking mechanism adapted to wind a strip fed from a strip mill, the combination of a rotatable block, clamping mechanism embodied in said block and operated with toggles, a cylinder, a piston in said cylinder, mechanism connecting the piston and toggles, non-compressible fluid pressure means adapted to actuate said piston to

120

125

130

operate and hold the toggles in position that the strip may be clamped to the block, and automatically controlled means for controlling said fluid pressure means.

- 5 23. In a blocking mechanism adapted to wind a strip fed from a strip mill, the combination of a rotatable block, a mechanism embodied in the block and adapted to be expanded to clamp the strip to the block, 70 and adapted also to be collapsed to leave the strip free on the block, non-compressible fluid pressure means for actuating said mechanism, and automatically electrically controlled means controlled by the strip for 10 controlling said non-compressible fluid pressure means.
24. In a blocking mechanism adapted to wind a strip fed from a strip mill, the combination of a rotatable block, means embodied within the block for causing the strip to be attached to the block when the same reaches the block, and an electric circuit controlled by bodily movement of the mill rolls automatically closed at the instant the 20 strip is sent through the mills for controlling said means.
25. In a blocking mechanism adapted to wind a strip fed from a strip mill, the combination of a rotatable block, means embodied within the block for causing the strip to be clamped to the block, said means being automatically controlled by the bodily movement of the mill rolls when the strip is sent through the mill. 30
- 35 26. In a blocking mechanism adapted to wind a strip fed from a strip mill, the combination of a rotatable block, means embodied within the block for causing the strip to be clamped to the block, a timing element, 40 means controlled by the bodily movement of the mill rolls when the strip is sent through the mill to control the timing element, to control the means embodied in the block and clamp the strip to the block when it reaches 45 the block.
27. In a blocking mechanism adapted to wind a strip fed from a strip mill, the combination of a rotatable block, means embodied in the block for causing the strip to be clamped to the block, a mechanical device operated by the spreading apart of the mill rolls when the strip is sent through the mill, an electric circuit controlled by said mechanical device, and means controlled by 50 said electric circuit for causing the means embodied within the block to function to clamp the strip to the block when it reaches the block. 55
28. In a blocking mechanism adapted to wind a strip fed from a strip mill, the combination of a rotatable block, means embodied within the block for causing the strip to be clamped to the block, a device actuated by the action of the mill rolls when the strip 60 is sent through the mill, an electric contact
- embodied in said device, an electric circuit controlled thereby, a timing device in said circuit, a dashpot for timing said operation, an electric circuit controlled by said timing device, and means in said circuit for causing 70 the means within the block to clamp the strip to the block when it enters the block.
29. In a blocking mechanism adapted to wind a strip coming from a strip mill, the combination of a rotatable block, means for 75 clamping the strip to the block, and means independent of the position of the strip relative to the block, but dependent upon bodily movement of the mill rolls, for controlling the clamping means. 80
30. In a strip mill, the combination of mill rolls for rolling a strip, blocking mechanism for the strip, comprising a rotatable block on which the strip is adapted to be wound, and a device operated by the mill rolls to 85 cause the strip to be attached to the block at a predetermined instant.
31. In a strip mill, the combination of rolls for rolling a strip, blocking mechanism for the strip comprising a rotatable block, 90 on which the strip is adapted to be wound, and a device operated by the mill rolls and controlling the block to attach the strip to the block at a predetermined instant. 95
32. In a strip mill, the combination of rolls for rolling a strip, blocking mechanism comprising a rotatable block, on which the strip is wound, guiding means for the strip between the mill rolls and the block, and a device operated by the mill rolls and adapted to control the block to cause the strip to 100 be attached to the block at a predetermined instant.
33. In a strip mill, the combination of rolls for rolling a strip, a blocking mechanism embodying a rotatable block, on which the strip is adapted to be wound, a device operated by the mill rolls as the strip enters the mill rolls, and timed with the feeding movement of the strip to cause the strip to 105 be attached to the block when it enters the block. 110
34. In a blocking device adapted to wind a strip coming from a strip mill, the combination of a device operated by the strip mill comprising a timing mechanism adapted to be set to correspond with the feeding movement of the strip, and means operated by said mechanism to cause the strip to be attached to the block when it reaches the block. 115 120
35. In a blocking device adapted to wind a strip coming from a strip mill, the combination of a rotatable block, means to operate said block to attach the strip to the block, a device operated by the strip mill, embodying a timing mechanism adapted to be set to correspond in operation with the feeding movement of the strip, and means controlling said first named means and operated by said timing mechanism to cause the strip to 125 130

be attached to the block when the strip reaches the block.

36. In combination a rolling mill, a block for blocking metal fed from the rolling mill, and adjustable means controlled by the rolls of the rolling mill for attaching the strip to the block.

37. In combination a rolling mill, a block for blocking strip metal fed from the rolling mill, and means controlled by the rolls of the rolling mill for attaching the strip to the block.

38. In combination, a rolling mill, a block for blocking strip metal fed from the rolling mill, and means controlled momentarily by the rolls of the rolling mill for attaching the strip to the block.

39. In combination, a rolling mill, a block for blocking strip metal fed from the rolling mill, and means actuated by the entry of the strip into the rolls of the rolling mill to attach the strip to the block.

40. In a strip mill, the combination of

rolls for rolling a strip, blocking mechanism embodying a rotatable block, electromagnetic means for adapting the block to wind a strip coming from said strip mill, circuits for said means, contacts operated by the mill rolls, and a circuit controlled thereby for controlling said first named circuits. 25 30

41. In a strip mill, the combination of rolls for rolling a strip, blocking mechanism embodying a rotatable block on which the strip is adapted to be wound, a device operable by the entry of the strip between the rolls of the strip mill, and means to attach the strip to the block and controlled by said device. 35

In testimony whereof I have signed my name to this specification in the presence of 40 two subscribing witnesses.

AUGUST SUNDH.
